Primary Examiner — Ian Simmons*Assistant Examiner* — Keith P Frank(74) *Attorney, Agent, or Firm* — Drinker Biddle & Reath LLP(57) **CLAIM**

The ornamental design for a bottle with removable side bottle, as shown and described.

DESCRIPTION

FIG. 1 is a front view of a bottle with removable side bottle according to the present invention.

FIG. 2 is a rear view of the bottle of FIG. 1.

FIG. 3 is a right side view of the bottle of FIG. 1.

FIG. 4 is a left side view of the bottle of FIG. 1.

FIG. 5 is a top view of the bottle of FIG. 1; and,

FIG. 6 is a bottom view of the bottle of FIG. 1.

The broken lines in the drawings showing the bottle with removable side bottle illustrate the portions of the bottle with removable side bottle that form no part of the claimed design.

1 Claim, 5 Drawing Sheets(56)
